UNITED STATES PATENT OFFICE

WILLARD R. BOYDSTUN, OF McCALL, IDAHO

SNOWFLOW

Application filed April 30, 1930. Serial No. 448,755.

The present invention is directed to an attachment for trucks, designed for the purpose of removing snow deposited along the sides of roadways and streets by the action of the conventional blade plow.

The structure involved in one of the assemblies includes a scoop adjustable in width and designed to direct the accumulated snow upwardly into a fan casing from which it is projected laterally by suitable impellers or fan blowers driven from a source of power carried by the truck.

Reference will be had to the accompanying drawings forming a part of this specification and wherein like characters of reference designate corresponding parts throughout the several views, in which:

Fig. 1 is a plan view;
Fig. 2 is a side elevation; and
20 Fig. 3 is an end elevation.

In the present disclosure a truck is illustrated having the forwardly mounted motor A for propelling same and the rearwardly mounted motor B for driving the fans.

25 The usual blade type of plow is illustrated at C positioned on the frame D and operates to force the snow in piles along the longitudinal edges of the road. Such deposits of snow are, in many instances, of such weight and 30 body that further movement from the road is impractical, unless some special means is provided for the removal of same. The present invention comprehends an assembly placed upon either side of the truck and rearward of the front blade plow C whereby the 35 scoop element will engage the roadside deposits caused by the front plow. In the present illustration, the auxiliary snow handling assembly comprising this invention is positioned at the extreme rear end of an extended chassis but may be located at any desired 40 point rearward of the plow C.

45 Each snow removing element includes a scoop comprising a main body portion E and the pivoted portion E' which permits lateral adjustment of the parts and the widening of the engaging edge e for the reception of 50 deposits of any proposed width which will be determined by the snowfall. The scoop member extends upwardly and terminates in a fan

casing F in which is located the fan or blower G. The fan casing is mounted loosely on the shaft section H on which the fan G is fixed and by means of which the latter is driven through suitable gearing in gear box h from power derived through the shaft J from the engine B. By this arrangement the scoop can be adjusted vertically with respect to the ground for use in conjunction with various types of roadbeds or may be moved entirely free of the roadbed as desired. The adjustable scoop E, E' permits a more compact assembly of the device when not in use. A suitable hoist K is shown for use in conjunction with the elevation of the scoop although other desirable means may be employed.

It will be noted that the scoop comprising the sections E, E' extends rearwardly a sufficient distance and gradually decreases in width, terminating eventually in the casing F in which is located the fan or blower G. In order to comprehend a more compact structure the forward wider portion of the scoop may be mounted to swing upwardly against the vehicle body, as shown in Fig. 3, upon the 75 hinges L, whereby the width of the assembly may be materially reduced.

What I claim is:

1. In combination with a motor vehicle, a snow plow carried by the front end of said 80 motor vehicle, an inclined scoop carried by said motor vehicle rearward of said snow plow, a blower arranged in conjunction with said scoop, and adjusting means for said scoop.

2. In combination with a motor vehicle, a snow plow carried thereby and adapted to force snow from its path laterally of the motor vehicle, a scoop positioned rearward of the snow plow for gathering the snow accumulated by same, a blower for forcing the snow gathered by the scoop outwardly from the motor vehicle, and means for adjusting the scoop.

3. The substance of claim 2 characterized in that the cutting edge of the scoop is adjustable in width to facilitate the handling of snow accumulations of varying sizes.

4. The substance of claim 2 characterized in that the scoop which is vertically adjust-

able is provided with a hinged section which permits adjustment of the cutting edge.

5. In combination with a motor vehicle, a snow plow carried thereby and adapted to force snow from its path laterally of the motor vehicle, a scoop positioned rearward of the snow plow including an inclined portion comprising a plurality of hinged overlapping sections, a guide-way forming a continuation of the scoop and terminating in a 10 blower casing, a blower arranged in said casing, means for driving said blower, and means for adjusting said scoop.

In testimony whereof I affix my signature.
